LEG ELEVATING ATTACHMENT FOR SURGICAL OPERATING TABLE

Jack Bauman, Santa Monica, Calif.
(1502 San Remo Drive, Pacific Palisades, Calif. 92104)

Filed July 10, 1975, Ser. No. 594,728

Term of patent 14 years

Int. Cl. D24—01
U.S. Cl. D83—1 D

FIG. 1

FIG. 2

FIG. 3

FIG. 4

FIG. 5

FIG. 1 is a side elevational view of a leg elevating attachment for surgical operating table, showing my new design, the opposite side being in mirror symmetry;

FIG. 2 is a top plan view;

FIG. 3 is a bottom plan view;

FIG. 4 is an elevational view of the left-hand end of FIG. 1; and,

FIG. 5 is an elevational view of the right-hand end of FIG. 1.

I claim:

The ornamental design for a leg elevating attachment for surgical operating table, as shown and described.
